UNITED STATES PATENT OFFICE.

GEORGE LEHBERGER, OF NEWARK, NEW JERSEY.

UNDERCARRIAGE OR CHASSIS FOR FLYING-MACHINES.

1,229,297.

Specification of Letters Patent. Patented June 12, 1917.

Application filed July 21, 1916. Serial No. 110,580.

To all whom it may concern:

Be it known that I, GEORGE LEHBERGER, a citizen of the United States, residing at Newark, in the county of Essex and State of New Jersey, have invented new and useful Improvements in Undercarriages or Chassis for Flying-Machines, of which the following is a specification.

This invention relates to an undercarriage or chassis for flying machines of the heavier-than-air type, the object of the invention being to provide a carriage or chassis embodying cushioned or resiliently mounted supporting wheels designed to afford a proper cushioning action and which may be readily and conveniently adjusted by the pilot to steer the machine along the surface of the ground, particularly in launching and landing along narrow roadways or in confined spaces.

A further object of the invention is to provide a carriage or chassis which may be used upon a heavier-than-air machine of the hydroaeroplane type, and in which the supporting wheels may be adjusted to an inoperative position so as to reduce resistance to travel and diminish liability of accidents from contact with extraneous objects when the structure is used in connection with a flying machine having a marine base.

With these and other objects in view, the invention consists of the features of construction, combination and arrangement of parts hereinafter fully described and claimed, reference being had to the accompanying drawings in which:—

Figure 1 is a side elevation of an undercarriage or chassis embodying my invention, parts appearing, for better disclosure of the invention, in section.

Fig. 2 is a front elevation of the same.

Fig. 3 is a top plan view with parts appearing in horizontal section.

Fig. 4 is an enlarged vertical longitudinal section through the head cushioning bearing of one of the wheel frame supports.

Fig. 5 is a detail section on the line 5—5 of Fig. 4.

Referring to the drawings, 1 designates the main frame of the undercarriage or chassis which may form part of or be secured in any suitable manner to the main frame of the machine proper. This frame 1, which may be of any preferred or suitable construction, is shown in the present instance as being of rectangular form and in-

cluding corner posts or uprights 2, bottom longitudinal skids or runners 3, upper longitudinal bars 4 and suitably arranged cross bars or rods 5, the parts being rigidly tight and united at their point of connection by upper and lower sets of coupling brackets or sleeves 6 and 7. The parts of the frame may be reinforced and braced in any suitable or required manner by bracing rods or wires 8.

The supporting wheels 9, which may be of the pneumatic-tired or other cushioned type, are disposed beyond the sides of the frame 1 and journaled upon spindles 10 pivotally connected for swinging movements in a longitudinal direction, as indicated at 11, with the ends of a horizontal transverse floating axle 12, which axle extends across the frame immediately above the skids or runners 3, bracing wires 13 or other suitable bracing connections between the axle and frame being provided to assist in guiding the axle and wheels in their movements and sustaining and bracing the same to meet the strains resulting from the shocks and jars falling thereon.

The spindles 10 are journaled in the arms of forks 14 forming part of wheel carrier frames resiliently mounted upon the main frame 1. Each of these carrier frames includes a steering post or rod comprising a lower section 15 fixed to or rigid with the fork 14, an upper section 16, and a link or intermediate section forming a joint pivotally coupling the post sections 15 and 16 together for articulating movements, as hereinafter described. A coupling sleeve 19 normally rests upon the crown of the fork and embraces the post sections in the region of the joint and holds them fixed against pivotal motion or deflection.

The spindles 10 are provided with arms or lugs 20, forming steering knuckles, and the arms or knuckles of each wheel spindle are jointed to the rear ends of a pair of parallel motion links 21 joined at their forward ends to the laterally extending or transverse arms 22 of a substantially T-shaped steering lever 23, the main arms of the levers 23 of the two wheels being pivotally connected by a transverse steering rod 25 connected to crossed controlling cables 26, designed to lead in practice to a steering or control device arranged in proximity to the pilot's seat, whereby the wheels may be swung laterally in either direction in unison.

for the purpose of steering the machine in an accurate and reliable manner so that it may be efficiently controlled in launching and landing the machine from and upon a narrow roadway and from and upon other confined spaces. As shown, the levers 23 are pivotally mounted to swing laterally, as indicated at 27 upon bracket arms 28 which are mounted to swing vertically upon rods or arms 29 fixed to and projecting from the bracket sleeves 7, by means of which the wheels and wheel frames are supported for vertical swinging motion upon the main frame 1, as will be readily understood.

The wheels and wheel frames are otherwise flexibly supported and suspended from the main frame 1 through the medium of upper and lower sets of suspending rods 31 and 32, each composed of sections united by turn buckles 33 for taking up all the play or slack when desired. The said rods 31 and 32 are respectively connected at their upper and lower ends with the bracket sleeves 6 and 7, and the opposite ends of said rods converge and are coupled by tie-brackets 34 which engage headed pins or bolts 35 fixed to and projecting laterally from a bearing sleeve or collar 36 in which the rod or post section 16 is slidably mounted, the two bearing sleeves 36 being united by a cross rod or bar 37, which connects the two sets of wheel frames suspending and supporting connections. Carried by each post section 16 above the collar 36 is a fixed collar or sleeve 38 which is provided with laterally projecting pins or rods 39 connected and braced at their outer ends by a cap piece or yoke 40 fitting upon the upper end of the post section 16. As shown in the present instance, the pins or rods 39 are preferably formed by the ends of a continuous rod passing through the post sections 16 and fixed collar 38 and serving also to unite these parts together.

The pins or bolts 35 and pins or arms 39 form supporting spindles for anti-friction sleeves or rollers 41 which are revolvably mounted thereon, and engaging and passing around the rollers at the opposite sides of the post section 16 are looped elastic bands 42 which are retained in place against displacement between the bearing and fixed collars and the tired brackets 34 and arms of the yoke 40, the said bands forming elastic or cushioning expansive and contractible connections between the steering posts of the wheel frames and the supporting and suspending members therefor fixed to the main frame, whereby the wheels and carriage frame are permitted to have a resilient relative vertical motion with respect to each other, the resilient backing for the wheels thus afforded acting in conjunction with the resilient tires of the wheel to compensate for and absorb all shocks and jars

in the landing of the machine and in its course of travel over rough or irregular ground surfaces.

It will, of course, be understood that the suspending and supporting connections between the wheel frames and main frame may be pivotally coupled to the main frame, whereby a further degree of elasticity and flexibility will be obtained without lessening the security of the connection between the wheel supports and main frame.

It will, of course, be understood that when the machine is in a standing position the weight of the machine body will be sustained by the elastic connection 42 from the wheel frames, and that in the travel of the machine over irregular ground the said elastic connections will permit of the requisite amount of vertical play of the wheels and wheel frames for a cushioning action.

In landing the machine the wheels will also be permitted to recede at the moment of contact to cushion the force of the impact and at the same time to permit the skids 3 to come in contact with the ground to check the running speed and finally bring the machine to a stop, the reaction of the elastic connections 42 restoring the wheels to normal position to elevate the body of the craft and bring the wheels in running contact with the ground. In their up and down play it will be evident that the wheels move with the wheel frames which pivot on the rods 29, the upper post sections 16 sliding through the bearing collar 36 against the resistance of the connections 42, which tend to maintain the collars 36 and 38 in a normally spaced relationship, which may be determined by the interpolation upon the post section 16 of a spacing washer 43 of either rigid or elastic material.

At all times except when it is desired to throw the wheels out of action the sections 15 and 16 of the post of each wheel support lie in alinement, the joint between them being maintained in a rigid position by the tube or sleeve 19. As shown in dotted lines in Fig. 1, however, by sliding said tube or sleeve 19 upwardly beyond the joint on to the sleeve section 16 the link 18 will be released for a flexing motion to break the joint, thus allowing the wheels to be swung upward to a position above the plane of the skids allowing the skids to be used alone or in conjunction with pontoons or other hydroplane surfaces. In practice, the sleeve 19 may be moved upward and downward to release the wheels for the purpose set forth and to subsequently lock them in normal position by any suitable type of operating means under the control of the pilot, or the arrangement may be simply such, as shown, as to require manual manipulation to throw the wheels into and out of use as occasion may demand. I have not deemed

it necessary to show means for adjusting the sleeves, as any preferred type may be used, such as a control device with cables or the like running therefrom over guides 5 to a bar connecting the sleeves, so that by suitable reverse movements of the controlling device the bar may be raised or lowered to release the wheels for a break-joint action and to fix them again in normal 10 position.

From the foregoing description, taken in connection with the drawings, the construction and mode of operation of my improved undercarriage or chassis for flying machines 15 will be readily understood, and it will be seen that the invention provides a wheel base of this character which will afford a reliable and efficient resilient action, and admit of the adjustment of the wheels to operative 20 and inoperative positions at will, without the use of a complex organization of parts. While the construction and arrangement of parts disclosed is preferred, it will, of course, be understood that changes in the form, construction and arrangement of the elements 25 within the scope of the invention as defined in the appended claims may be made without departing from the spirit or sacrificing any of the advantages of the invention.

30 I claim:—

1. In a launching and landing gear for flying machines, the combination, with a frame structure, of wheeled carrying frames, each including a rod composed of jointed sections, 35 means yieldingly backing the jointed rods of the wheel carrying frames, manually operable means for simultaneously rendering the joints of the rod flexible or inflexible, connecting means between the wheels to 40 adapt them to have lateral motion in unison, and means for imparting steering motions to said connecting means.

2. In a launching and landing base for flying machines, the combination with a 45 frame structure, of wheel carrying frames, each including a rod composed of sections and a link joining said sections together,

means yieldingly backing the rods of the wheel carrying frames, manually operable means engageable with rod sections and their 50 connecting links for simultaneously rendering the rods flexible or inflexible, connecting means between the wheels adapting them for lateral movements in unison, and steering mechanism coupled to said connecting 55 means.

3. In a launching and landing base for flying machines, the combination with a frame structure, of wheel carrying frames, each including a rod composed of sections pivotally united by a connecting link, sleeves 60 slideable on the rods for rendering the jointed connections thereof flexible or inflexible, means yieldingly connecting the wheel carrier frames, and means for simultaneously 65 moving the wheels laterally for steering actions.

4. In a launching and landing base for flying machines, the combination, with a frame structure, of wheel carrying frames, 70 each including a jointed rod, means slidably mounting and yieldingly backing each supporting rod, means for holding the joints of the rods normally rigid, said means being operative to release the joints for a pivotal 75 motion of the rods to move the wheels into and out of operative position, and means for swinging the wheels laterally upon the rods for steering actions.

5. In a launching and landing base for 80 flying machines, the combination, with a frame structure, of wheel carrier frames pivoted for vertical and lateral swinging motions of the frame structure, and including rods provided with pivot joints, means 85 slidably supporting said rods upon the frame structure, means for yieldingly backing said rod, and means for swinging the wheel frames laterally in unison, and means for rendering the joints of the rods flexible 90 or inflexible.

In testimony whereof I affix signature.

GEORGE LEHBERGER.
